ARTHUR C. FRIEDEL, OF SYRACUSE, NEW YORK, ASSIGNOR TO J. F. FRIEDEL PAPER
BOX COMPANY, OF SYRACUSE, NEW YORK, A CORPORATION OF NEW YORK

TOY BUILDING STRUCTURE

Application filed April 26, 1927. Serial No. 186,696.

This invention relates to toy building blocks involving the use of a multiplicity of similar tubular units of cardboard or equivalent comparatively light and inexpensive material together with floor, ceiling or roof units and cornice units of similar material constructed in such manner that they may be assembled in a wide variety of architectural designs.

10 The main object is to produce a relatively large number of architectural designs with a comparatively small number of identical units, the unit being furnished in sets of different numbers according to the magnitude 15 of the structures to be built up.

One of the specific objects is to construct the units in such form that only three different forms are required for the various designs of the main structure, floors, ceiling, roof, 20 foundation and cornices.

Another object is to construct each unit in such manner that it may be collapsed into a flat condition thus permitting a large number of the units for each set to be packed in a 25 relatively small space for convenience of storage or transportation.

30 A further object is to construct one of the sections so that it may be used for a floor, ceiling, or roof and at the same time to provide it with means for interlocking engagement with any one of the tubular units for holding it in definite relation thereto.

35 A further object is to utilize parts of this floor, ceiling or roof unit for interlocking engagement with other adjacent units, either in a horizontal relation side by side or in superposed relation one upon the other.

40 Another object is to provide the cornice section with means whereby it may be interlocked with anyone of the horizontal rows of tubular sections after the latter have been assembled to complete a structure of predetermined design.

45 Other objects and uses relating to specific parts of the distinctive units and the matter of assembling the same will be brought out in the following description.

In the drawings:—

50 Figure 1 is a perspective view of one structural design of which the assembly of the

various units of a set are capable of producing.

Figure 2 is an enlarged vertical sectional view of a series of units showing the manner of assembling them in the building of a structural design. 55

Figure 3 is a perspective view of one of the detached tubular units.

Figure 4 is a plan of one of the cornice units, partly broken away and flattened out. 60

Figure 5 is a face view of the flat blank from which the tubular unit is formed.

Figure 6 is a face view of a cornice unit similar to Figure 4 except that it is to be used at the corners or angles of the building. 65

Figure 7 is a face view of the flat blank from which the floor, ceiling and roof unit is formed.

Figure 8 is a perspective view of the unit made from the blank shown in Figure 7. 70

The units which are to form the main structure of the building are of the same form and size and each preferably consists of a hollow block of cubical form or square in cross section made of cardboard or other light and comparatively inexpensive sheet material united and scored at the corners for flexibility and to permit adjacent sides thereof to be folded or collapsed one upon the other in a substantially flat plane for economy in space 75 and for convenience of storage and transportation. 80

For this latter purpose each unit is preferably made from a flat blank —1— of said sheet material of uniform height from end to end and provided with transverse score lines —a— in uniform spaced relation from one end and from each other corresponding to the height of the strip to form the four sides thereof, the opposite end of the blank 85 being extended to form a flap —a'— which, when the unit is completed is adhesively secured to the first-named end of the strip as shown more clearly in Figure 3.

The unit as —2— which is to form the floor, 90 ceiling and roof is preferably made of the same material as the first described units and when flattened out or in blank as shown in Figure 7 forms a cross having a substantially flat central body —b— and wings —b'— of 100

substantially the same or slightly less width than the central body —a— projecting from the four sides thereof, said blank being scored at —b''— along the junctions of the wings 5 —b'— with a square central body —b— to permit said wings to be readily folded from their flat positions to other positions at substantially right angles to the main central portion as shown in Figure 8.

- 10 The central portion —b— is of approximately the same size as the cross sectional area of the interior of any one of the units previously described while the wings —b'— are of less height than width so that when folded 15 at right angles to the main body —b— the entire unit may be telescopically inserted into either end of any one of the first described units or either end of the flaps or extensions —b'— may be inserted into the corresponding 20 end of an adjacent unit of the same tier for holding said units against relative lateral movement as shown in Figure 2.

For example, when the unit —2— is to be used as a floor for any particular room unit 25 and particularly at the bottom of the structure, two or three of the flaps —b'— may be inserted from the bottom upwardly into that unit leaving the remaining flap or flaps extending upwardly along the outside of said 30 unit so that the next adjacent unit or units in the same horizontal tier or tiers may be telescopically assembled thereon as shown at the bottom of Figure 2 thereby locking the adjacent units to each other against relative 35 lateral movement.

In like manner the units —2— may be assembled in the bottom of each superimposed unit in the same horizontal plane to form the floors thereof and at the same time permitting 40 the wings or flaps —b'— to be used for reinforcing or strengthening the side walls of the superimposed units against distortion from their normal square forms.

One or more, preferably two, of the opposite wings —b'— are provided with arcuate slits —b³— substantially midway between the adjacent score lines —b''— and outer edges of the corresponding wings with their concave sides facing outwardly to form tongues 50 or limiting stops —b⁴— which are sufficiently resilient to permit them to be sprung outwardly by hand for a purpose presently described.

When it is desired to use the unit —2— as a combined floor and ceiling for anyone of the first described units it is preferably inserted in the upper end of said unit with its square portion —b— at the bottom whereupon the tongues —b⁴— will be pressed outwardly by hand so as to engage the upper edges of corresponding sides of the unit —1— as shown in Figure 2 thereby limiting the downward movement of each unit —2— so 60 that approximately the lower half thereof

will remain telescopically in the unit —1— while the upper half will project a sufficient distance above said unit to permit the insertion of adjacent sides of superposed units into the upper end of the previously installed unit 70 —2— as shown in Figure 2.

In like manner, these units —1— and floor-and-ceiling units —2— may be successively installed from the bottom upward and side by side to any extent desired or within the range 75 of the set provided.

That is, any horizontal tier or tiers may be extended laterally or forwardly and rearwardly according to each pre-determined structural design and these horizontal tiers 80 may be multiplied vertically to any height desired and the height of each column varied at will to carry out said design.

When the unit —2— is to be used as a roof for any one of the upright units it is inverted or placed telescopically within said unit with its horizontal square portion at the top and its four wings inserted into the upright unit as shown in Figure 2 or if necessary one or more of the wings may be inserted into the next adjacent upright unit to assist in embracing the structure or holding the upper upright sections against relative lateral displacement, it being understood that the upright sections are more or less yielding and 95 that the sections —2— fit snugly within the upright sections and are held against undue downward displacement by friction when desired.

It will also be observed that when the units 100 —1— are assembled one upon the other and the ceiling sections are placed in operative position at least some portions of the lower ends of the upright sections will rest upon the upper ends of the underlying sections and 105 will be held in vertical alinement by the wings of the inclosed floor or ceiling section.

For straight cornice work a cornice section —3— may be used in which case it will be provided with score lines —c— in transversely spaced relation parallel with one of the straight edges thereof, the opposite edge being provided with V-shaped slits —c''— which results in the formation of tabs c'' 110 between them, such tabs being adapted to enter the open upper ends of the tubular sections in the same horizontal row adjacent one 115 side thereof as, for example, the further side of the building, the walls of the sections entering the slits c'.

These cornice strips —3— are preferably made of the same material as the first described sections and floor or ceiling sections and while they are preferably made of pre-determined length they may be cut transversely to any desired length in line with one or the other of the slits —c'— according 125 to the number of upright sections in the horizontal row to which they are applied.

The V-shaped slits —c'— extend from the 130

corresponding edge of the strip —3— to the adjacent score line —c— while the portions between the score lines —c— are usually bent outwardly along the lower line and then upwardly along the upward line as shown in Figure 2 to produce the desired overhanging of the cornice.

As illustrated in Figure 2 the tabs —c''— are inserted in the upper ends of the upright units between one side thereof and the adjacent side of the roof section which increases the friction between the wings of the roof section and upright unit and thence to additionally hold said units in operative position.

18 The cornice section as —3'— for the corners or angles of the building is made of the same material as the section —3— and is similarly scored lengthwise but is provided with a transverse score —d— and a somewhat larger 20 V-shaped recess —c'— extending to the upper score line so that the opposite ends of the strip —3'— may be bent upon the score line —d'— or midway between the opposite edges of the opening —c'— at right angles 25 to each other to correspond to the angle of the building to which it is applied.

Otherwise the construction is quite similar to that shown in Figure 4.

It will now be evident that with substantially three units multiplied to any desired extent to constitute a set will suffice for a large number of different structural designs which may be amplified by printing or otherwise impressing upon the outer surfaces of 35 the units conventional configurations according to the taste of the makers.

What I claim is:—

1. In toybuilding blocks, an upright unit of square cross-section open at the top and 40 bottom to form the four sides of a room, a roof unit having a square body of substantially the same cross sectional area as the upright unit and having flaps along its four sides folded at right angles to its body for 45 insertion into the upper end of the upright unit and a cornice unit having score lines in parallel spaced relation lengthwise thereof to fold along said lines, said cornice unit having tabs along the edges to be inserted between 50 the flaps of the roof unit and the inside walls of the upright unit.

2. A toybuilding structure comprising a rectangular tubular upright unit, a box-like ceiling unit having its closed end telescopically inserted in the upper end of the upright unit and its open end projecting above said upright unit, opposite walls of the ceiling unit having their intermediate portions provided with outwardly projecting stops for 55 engaging the upper edges of the corresponding sides of the upright unit for limiting the downward movement of the ceiling unit.

3. A toybuilding structure comprising similar upright rectangular tubular units 60 ranged side by side in juxtaposed relation,

and a box-like floor unit having its upright sides detached from each other at the corners, three of said sides being inserted from the underside upwardly into one of the upright units, and its fourth side inserted from the underside upwardly into the other upright unit.

In witness whereof I have hereunto set my hand this 22nd day of April, 1927.

ARTHUR C. FRIEDEL.
